UNITED STATES PATENT OFFICE.

EPHRIAM W. MORRIS, OF ROCKWOOD, TENNESSEE, ASSIGNOR OF ONE-THIRD TO
OLIVER H. ANDERSON, OF ONEIDA, TENNESSEE.

WHEEL-LOCKING DOG.

Application filed October 28, 1924. Serial No. 746,428.

To all whom it may concern:

Be it known that I, EPHRIAM W. MORRIS, a citizen of the United States, residing at Rockwood, in the county of Roane and State 5 of Tennessee, have invented certain new and useful Improvements in Wheel-Locking Dogs, of which the following is a specification, reference being had to the accompanying drawings.

10 This invention relates to devices for locking railroad car wheels for the purpose of either preventing the accidental movement of a car standing on a siding, for instance, or for the purpose of skidding one pair of 15 wheels of a car so as to permit the car to be shifted off the main line to a place where it can be repaired.

It sometimes happens during the passage 20 of a train over a railroad that the wheels become defective either by reason of the axle becoming bent or the flange broken or from other causes and thus cause a serious delay not only to the train upon which the break occurs but possibly to other trains following 25 while the necessary repairs are made, which repairs are necessary in order to remove the same to clear the main line.

A method ordinarily employed is to place 30 on the wheel a wheel clamp. This, however, is very hard to use and require special tools, which causes a delay to the train.

The object of my present invention is to 35 obviate this difficulty by providing a wheel dog which is readily attachable without special tools over the flange of the wheel and which is so constructed that if the wheel is turned at all after the dog is in place the dog will bear against the arch bar and will jam upon the wheel and hold the wheel 40 against further movement.

My invention is illustrated in the accompanying drawing, wherein:—

Figure 1 is a perspective view of my improved dog applied to a car wheel;

45 Figure 2 is a perspective view looking at the inner face of the wheel and showing how the bill of the hook engages with the wheel;

50 Figure 3 is a vertical sectional view through the wheel showing the manner in which the hook engages therewith and with the arch bar in order to jam or dog the wheel;

55 Figure 4 is a top plan view of the dog.

Referring to these drawings, it will be

seen that my emergency wheel dog consists of a casting, preferably of steel, having a body 10, a shank 11 projecting from the body, and a hook 12. The shank 11 is less in depth than the body 10 so as to provide an end face or shoulder 12^a for the body, and the inner face of the shank is obtusely angled, as at 13, between the beginning of the bill of the hook and the face 12^a. Preferably the lateral face of the shank and of the integral body are reinforced by a longitudinally extending rib 14. The inner face of the body is at right angles to the face 12^a, while the outer face of the body is slightly inclined.

This dog has a length sufficient so that it may be engaged over the flange of the wheel A and the lower face of the body will rest upon the arch bar B. The bill of the hook will extend beneath the flange as, for instance, as illustrated in the drawings, and between the strengthening ribs a of the wheel and the face 13 bears against the periphery of the wheel, while the angular face 12^a bears against the side face of the wheel rim. as illustrated in Figure 3.

This device may be used for the purpose of preventing runaways on elevated tracks, at mines, and where it is necessary on short line railroads to leave a car for some special purpose on the main line or on a siding. Under these circumstances sometimes the brakes become loosened during the loading of the car and the car runs away down hill and sometimes passes onto the main line with disastrous results. When this device is attached as illustrated and there is any forward movement of the wheel, the device immediately turns upon the rim of the wheel and jams on the wheel and it is impossible for the wheel to move further. When attached to a wheel it is impossible to remove the dog unless the engine backs the car. The slackening back of the car permits the dog to be detached. Thus there is no danger of the dog becoming accidentally loose.

The device is also particularly valuable in locking a wheel which has become damaged to permit the car to be skidded from off the main line to a place where it can be repaired. This device requires no tools to apply and no screws to force in place, but can be applied by hand in a few seconds. The dog may be applied either on top of the arch bar or underneath the arch bar

or in between the arch bars, and in all of these various situations will act to hold the wheel from any further forward movement.

While I have illustrated a construction which I have found to be extremely practical, I do not wish to be limited to this as it is obvious that many changes might be made in the details of construction and arrangement of parts without departing from the spirit of the invention.

I claim:—

1. An emergency dog for locking railway car wheels comprising a straight body, an integral shank extending at a slight angle 15 from the body and slightly offset with relation thereto to thereby provide a shoulder extending downward from the shank, the shank terminating in a hook, the bill of the hook extending from the body and the space 20 between the shoulder and the bill of the hook being of sufficient depth to permit the hook to be disposed over the flange of the car wheel and extend inward of said flange to thereby permit the end of the body to bear against the edge of the wheel rim opposite the flange.

2. An emergency wheel dog comprising an integral casting formed to provide a straight body portion rectangular in section, a shank 25 extending at a slight angle to the body por-

tion and terminating in a hook, the bill of which extends toward the adjacent end of the body, the hook being of sufficient depth to permit the hook to be disposed over the flange of the car wheel and extend beneath said flange, the distance between the bill of the hook and the end of the body being sufficient to permit the end of the body to bear against the edge of the wheel rim opposite the flange.

3. An emergency wheel dog formed to provide a body portion rectangular in section, a shank extending from the body portion and terminating in a hook, the shank at its junction with the hook being formed 45 with a shoulder upon its lower face adapted to bear against the rim of a wheel, the bill of the hook extending toward the adjacent end of the body, the hook being of sufficient depth to permit the hook to be disposed over the flange of the car wheel and extend beneath said flange, the distance between the bill of the hook and the shoulder on the body being sufficient to permit the shoulder to bear against the wheel rim opposite said 50 flange.

In testimony whereof I hereunto affix my signature.

EPHRIAM W. MORRIS.
